Filed June 23, 1959, Ser. No. 56,506

Term of patent 14 years

(Cl. D71—1)

FIG. 1

FIG. 2

FIG. 3

FIGURE 1 is a side elevational view of a guided missile embodying my new design;

FIGURE 2 is a side elevational view thereof taken from the right of FIGURE 1; and

FIGURE 3 is a perspective view, on an enlarged scale, of my new design taken from the bottom and left of FIGURE 1.

My design for a guided missile shaped as shown is characterized by the particular control vanes in association with the hinged fins near the nozzle end.

I claim:

The ornamental design for a guided missile, substantially as shown and described.
